P. DE LEMME

MECHANICAL TOY DUCK

Filed Oct. 20, 1926

INVENTOR.
PHILIP DE LEMME

BY

Warren S. Orton.
ATTORNEY.

UNITED STATES PATENT OFFICE.

PHILIP DE LEMME, OF JERSEY CITY, NEW JERSEY.

MECHANICAL TOY DUCK.

Application filed October 20, 1926. Serial No. 143,012.

The invention relates in general to a mechanical toy of the type which is made up to simulate an animal and specifically the invention relates to a wheel supported toy resembling a grotesque form of duck.

The object of the invention is to provide a simple form of toy of the type outlined which will have a grotesque and unusual movement of the tail either with or without 10 a conventional nodding movement of the head portion.

Various other objects and advantages of the invention will be in part obvious from an inspection of the accompanying drawings 15 and in part will be more fully set forth in the following particular description of one form of device embodying my invention, and the invention also consists in certain new and novel features of construction and combination of parts hereinafter set forth and claimed.

In the accompanying drawing,

Fig. 1 is a view in side elevation of a toy constituting a specific embodiment of the invention with parts broken away to show internal construction and showing in full and dotted lines, the two extreme positions of the head and tail; and

Fig. 2 is a plan view looking down upon 30 the structure shown in Fig. 1.

In the drawing there is shown a body portion 10 formed of side boards 11 and 12 and a back 13. The toy is conventionally supported on wheels 14, the axle 14' of the front 35 pair being provided with a crank 15. Pivotedly mounted on a pin 16 is a head 17, the head portion includes rearwardly extending portion 18 which is positioned between the side boards and the back 13.

40 At the rear of the figure is a tail 19, the upper rear portion 20 of which is exposed beyond the outline of the body portion and the inner part 21 is concealed within the lines of the body portion.

45 Instead of the usual pivotal mounting of the tail in similar devices of this character, it is intended that the tail be mounted so that it will have reciprocatory movement into and out of the body portion so that the 50 amount of tail exposed varies from time to time as the toy is drawn along the ground. It is preferable to have this tail action work in synchronism with the head movement so as to enhance the grotesque action of the 55 figure and for this purpose the tail is pivotally connected by pin 22 to the rear

end of the extension 18. The tail is guided in its reciprocatory movement between an undercut beveled guiding surface 23 defining the rear end of the back 13, on the underside the tail is supported so as to ride over 60 a pin 24 and which pin acts additionally to secure the rear ends of the side boards. A reach rod 25 is pivotally connected at its rear upper end to the underside of the extension 18 and at its forward end to the crank 15. The toy is drawn along the ground by means of a draft member 26.

As the toy is drawn along the ground, the turning wheels will actuate the crank and 70 this in turn will cause the head portion to oscillate or nod about the fulcrum provided by the pin 16. At the same time the head will act on the tail to draw the same from the extended full line position shown in Fig. 75 1 into a retracted dotted line position shown in this figure. With the relative arrangement of the parts illustrated, the tail will be drawn in as the head is elevated or moved back, and as the head moves down and forward, the tail will be distended. As the toy is drawn along, this action of head and tail appears unusual, grotesque and pleasing.

While I have shown and described, and have pointed out in the annexed claims, certain novel features of my invention, it will be understood that various omissions, substitutions and changes in the form and details of the device illustrated and in its operation may be made by those skilled in 90 the art without departing from the spirit of the invention.

Having thus described my invention, I claim:

1. A wheeled toy simulating a grotesque 95 form of duck and including a body portion, a head pivotally mounted to the body portion and having a portion extending rearwardly from its pivotal connection with the body portion, a tail mounted having a portion exposed and a portion intruded into and concealed by the body portion, means for mounting the tail to have bodily movement into and out of the body portion thereby to vary the extent of tail projecting out of the 100 body portion, a pivotal connection between the rearwardly extending portion of the head and the concealed portion of the tail, a wheel support for the toy, and mechanism including a crank driven by the wheel support for 105 actuating the head and tail in synchronism as the toy is moved along the ground. 110

2. A wheeled toy simulating a grotesque form of animal, and including a body portion, a pivotally mounted head and a reciprocally mounted tail, means for guiding the tail in its reciprocatory movement, means for connecting the tail and head to operate the same in unison and to cause the tail to reciprocate in distinction from oscil-

lating, a wheel support for the toy and crank mechanism actuated by the wheel support for causing the head to oscillate and the tail to reciprocate. 10

Signed at Jersey City in the county of Hudson and State of New Jersey this 16th day of October A. D. 1926.

PHILIP DE LEMME.
